UNITED STATES PATENT OFFICE.

GEORGE H. TOMLINSON, OF CHICAGO, ILLINOIS, ASSIGNOR TO STANDARD ALCOHOL COMPANY, OF NEW YORK, N. Y., A CORPORATION OF MAINE.

APPARATUS FOR FEEDING MATERIALS TO DIGESTERS.

1,032,445.

Specification of Letters Patent. Patented July 16, 1912.

Application filed December 21, 1910. Serial No. 598,589.

To all whom it may concern:

Be it known that I, GEORGE H. TOMLINSON, a subject of the King of England, residing at Chicago, in the county of Cook and State of Illinois, have invented a certain new and useful Improvement in the Apparatus for Feeding Materials to Digesters, of which the following is a specification.

10 My invention relates to improvements in apparatus for feeding materials to a digester, and is illustrated diagrammatically in one form in the accompanying drawings, wherein—

15 Figure 1 is a longitudinal sectional view of the apparatus; Fig. 2 is a section along the line 2—2 of Fig. 1; Fig. 3 is a section along the line 3—3 of Fig. 1; Fig. 4 is a detail of a modification.

20 Like parts are indicated by like letters throughout the several figures.

The belt conveyer A rides over the pulley A¹ in opposition to the scraper A² which discharges onto the inclined weighing platform A³ which is supported at the edge near the pulley by the knife-edge A⁴ on the bracket A⁵ and at the edge farthest removed therefrom by the knife-edge A⁶ and connecting link A⁷ which terminates at its upper 25 end in the eye A⁸ carried by the hook A⁹ and supporting spring A¹⁰ which is carried in the bracket A¹¹ adjustable in position on the guide A¹².

30 The weighing platform A³ discharges onto the oscillating inclined tray B which is located within and supported from the chute B¹ by means of the links B², and which is oscillated by the link B³ and pulley B⁴ driven by the belt B⁵ from the pulley 35 A¹.

35 The chute B¹ terminates at its lower extremity in the funnel C and discharge pipe C¹ in opposition to the man-hole C² in the digester C³ and contains the spraying nozzles C⁴ in communication with the pipe

40 C⁵ which is supplied from the reservoir C⁶. The link A⁷ is carried on the knife-edge D on one end of the scale beam D¹ which is provided with the knife-edge D² in opposition to the bracket D³ on the chute B¹ and has the adjustable counterbalance weight D⁴ and is in pivotal engagement at one end with the piston rod D⁵, piston D⁶ and dash-pot D⁷.

45 The funnels E which are in opposition to the spray nozzles C⁴ and discharge pipe C⁵ which is supplied from the reservoir C⁶ are carried on the frame E¹ to the pipe E² and reservoir C⁶, are carried on the frame E³ which is supported at one end by the link E⁴ from the chute B¹ and at the other end by the arm E⁵ which projects from the fulcrum of the scale beam D¹, and are so 50 located along the frame E³ that any downward movement of the frame will take them successively out of opposition to the spraying nozzles.

55 In the modification suggested in Fig. 4, I have shown the supply pipe C⁵ controlled by the valve F which is operated by means of the lever F¹ and link F² from the arm E⁵.

60 It will be evident that while I have shown in my drawings an operative device still many changes might be made in the size, shape and arrangement of the parts without departing materially from the spirit of my invention.

65 The use and operation of my invention are as follows:—As the belt conveyer operates, the material carried by it discharges upon the inclined weighing platform, and owing to its inclination passes across it in a continuous sheet being discharged upon the 70 upper end of the oscillating inclined tray, down which it travels to the funnel at the end of the chute and thence through the pipe into the digester. Suitable means not shown force a continuous stream of acid or 75 other liquid through the spray nozzles, this stream being discharged into the funnels in the position shown and thence back to the supply reservoir. When the material is passing across the weighing platform its weight depresses the platform and raises the scale beam thus rotating the arm which projects from the beam and thus carrying the funnels back out of register with the spray nozzles so they discharge onto the material passing along the tray below. The arrangement is such that one nozzle after another comes into operation and for a slight quantity of material only a few of the nozzles will operate while for a large quantity which greatly depresses the scale, all of the nozzles will be brought into operation.

80 85 90 95 The relation between the amount of material passing and the amount of acid discharged thereon is controlled by an adjustable spring and a counterbalance on the scale beam, the dash-pot being provided to prevent any violent changes in the supply 100 105

owing to any local disturbance of the amount of cellulose being discharged across the weighing platform.

I claim:—

- 5 1. The combination with a digester, of a conveyer adapted to support a comminuted solid material and to deliver the same to said digester, and means for discharging a liquid upon the material carried by said conveyer.
- 10 2. The combination with a digester, of a conveyer adapted to support a comminuted solid material in the form of an extended sheet and to deliver the same to said digester, and means for discharging a liquid upon the material carried by said conveyer.
- 15 3. The combination with a digester and means for conveying solid materials thereto of means for adding to said materials a measured quantity of liquid, said means responsive to the amount of solid materials.
- 20 4. The combination with a digester and means for conveying solid materials thereto of means for adding to said materials a measured quantity of liquid, said means containing a movable platform and weighing mechanism therefor.
- 25 5. The combination with a digester and means for conveying solid materials thereto of means for adding to said materials a measured quantity of liquid, said means containing a movable platform, spraying nozzles and waste funnels in opposition to said nozzles.
- 30 6. The combination with a digester and means for conveying solid materials thereto of means for adding to said materials a measured quantity of liquid, said means comprising a movable platform, spraying nozzles, funnels in opposition to said nozzles and means responsive to the movement of said platform for moving said funnels out of register with said nozzles.
- 35 7. The combination with a digester and means for conveying solid materials thereto of means for adding to said materials a measured quantity of liquid, said means comprising a movable platform, spraying nozzles, funnels in opposition to said nozzles and means responsive to the movement of said platform for successively moving said funnels out of register with said nozzles.
- 40 8. The combination with a digester of means for feeding materials thereto in a continuous sheet and means for discharging a measured quantity of moisture upon said continuous sheet.
- 45 9. The combination with a digester of means for feeding materials thereto in a continuous sheet and means for discharg-

ing moisture upon said continuous sheet, said means responsive to the amount of material in said sheet.

10. The combination with a digester of means for feeding materials thereto in a continuous sheet and means for discharging a measured quantity of moisture upon said continuous sheet, said means responsive to the amount of material in said sheet.

11. The combination with a digester of means for feeding materials thereto in a continuous sheet and means for discharging moisture upon said continuous sheet, said means including constantly operative spraying nozzles and means for intercepting the discharge from said nozzles.

12. The combination with a digester of means for feeding materials thereto in a continuous sheet and means for discharging a measured quantity of moisture upon said continuous sheet, said means including constantly operative spraying nozzles and means for intercepting the discharge from said nozzles.

13. An apparatus for feeding materials to a digester comprising a belt conveyer, an oscillating inclined tray leading from the conveyer to the digester and a movable platform located between said tray and said conveyer.

14. An apparatus for feeding materials to a digester comprising a belt conveyer, an oscillating inclined tray leading from the conveyer to the digester, a movable platform located between said tray and said conveyer, and spraying means in opposition to said tray.

15. An apparatus for feeding materials to a digester comprising a belt conveyer, an oscillating inclined tray leading from the conveyer to the digester and a movable platform located between said tray and said conveyer, and constantly operative spraying means in opposition to said tray and means for intercepting the discharge from said tray.

16. An apparatus for feeding materials to a digester comprising a belt conveyer, an oscillating inclined tray leading from the conveyer to the digester and a movable platform located between said tray and said conveyer, and constantly operative spraying means in opposition to said tray and means for intercepting the discharge from said tray, said intercepting means responsive to the weight of material passing over said movable platform.

GEORGE H. TOMLINSON.
